UNITED STATES PATENT OFFICE.

THOMAS S. HOMANS, OF HEMPSTEAD, NEW YORK, ASSIGNOR TO INTERNATIONAL
TYPESETTING MACHINE COMPANY, OF NEW YORK, N. Y., A CORPORATION OF
NEW YORK.

LINOTYPE-MACHINE.

1,153,078.

Specification of Letters Patent. Patented Sept. 7, 1915.

Application filed July 5, 1912. Serial No. 707,928.

To all whom it may concern:

Be it known that I, THOMAS S. HOMANS, a citizen of the United States, residing at Hempstead, in the county of Nassau and State of New York, have invented new and useful Improvements in Linotype-Machines, of which the following is a specification.

The primary object of this invention is to provide an escapement which would be correct in construction, compact, and finally, simple.

Escapements for linotype magazines as ordinarily made are of two general kinds, in one of which, each escapement is made up of several parts and becomes bulky and objectionable, especially where the escapement is attached to and is a part of the magazine. The other kind of escapement is of one piece and has heretofore had its pivot so remote from the path of the matrices, that the movement of the engaging points of the escapement has necessarily been at an angle to the path of the matrices. This is one of the main objections to the use of the one-piece escapement as heretofore constructed, inasmuch as the engaging points of the escapement, if they are not moved from the path of the matrices at a true angle, must necessarily push or lift the column of matrices upward in order to release, while at the opposite end of the escapement, the column of matrices sliding down to engage therewith will tend to push the escapement out of the matrix path. Both of these actions are necessarily caused by having the axis of motion of the escapement at any point other than at the path of the matrices.

An additional feature of this invention is, that it provides a bearing for each escapement to rock on, each bearing being exactly in the plane of the corresponding matrix channel of the magazine and having its axis at a right angle to the plane of the respective escapement and the corresponding matrix channel in the magazine. The ordinary escapements are pivoted to one wire which runs directly across and under the magazine, whereas, the converging channels of the magazine are all at varying angles with this pivot wire, thus forcing the escapement to be held between check-pieces loosely mounted on a pivot to compensate for this faulty mechanical arrangement.

Another object of the invention is to provide means, located at a suitable point be-

tween each escapement and the keyboard, for taking up all overthrow or excess motion which may be provided to compensate for wear of the cam roller and the parts between it and the escapement, certainty in operation of the escapements being thereby insured.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a perspective view of a section of the mechanism of a linotype machine which controls the delivery of matrices from the magazine, the escapement mechanism shown therein embodying the present invention; Fig. 2 represents a vertical section of the structure shown in Fig. 1, the parts being in normal or inactive condition; Fig. 3 is a view similar to Fig. 2 showing one of the escapements actuated to release and cause delivery of a matrix from its respective channel of the magazine; Fig. 4 is a perspective view of one of the escapement members and its mounting. Fig. 5 is a view showing diagrammatically the converging matrix channels of the magazine and the corresponding convergence or angularity of the escapement grooves in the escapement bar.

Similar parts are designated by the same reference characters in the several views.

Heretofore in machines of this character, the escapements, which control the delivery of the matrices from the magazine, have been pivoted on a pin operating in a hole in the escapement, the pin forming the axis of oscillation of the escapement points. Owing to the fact that the channels of the magazine contain a large number of matrices which are fed by gravity to the respective escapements, considerable wear between each escapement and its pivot pin has resulted in previous constructions due to the repeated checking of the line of stored matrices by the escapement during the delivery of the matrices, and experience has shown that the wear so produced results frequently in faulty delivery of the matrices, occasioning numerous delays in the operation of the machine.

The present invention provides a construction which obviates the defects and objections incident to the escapement mecha-

nisms as heretofore used, and moreover, the present invention enables this part of the machine to be manufactured and assembled more readily as compared with previous constructions, the escapement member in the preferred embodiment of the invention being in one piece, thus reducing materially the number of parts and connections employed, and the escapement is so mounted as 10 to minimize wear and to maintain correct working relations of the parts. The preferred embodiment of the invention is shown in the accompanying drawing and will be hereinafter described in detail, but 15 it is to be understood that the invention is not restricted to the particular construction shown as equivalent constructions may be used within the scope of the claims.

In the present instance, the improvements 20 are shown in connection with the well known linotype machine, the keyboard mechanism of which embodies the usual key levers 1 coöperating with the vertically movable key bars 2 and the latter coöperating 25 with the bell-crank levers 3 which are pivoted at 4 on the cam frame 5, these bell-crank levers controlling the cam yokes 6 in the usual manner, these cam yokes being pivoted at 7 and having cams 8 journaled thereon, the cams being arranged to coöperate 30 with the continuously revolving cam rollers 9. Each cam is normally held in inoperative position by a pin 10 thereon which co-operates with a toothed bar 11, lowering of 35 the cam yoke serving in the usual manner to set the cam 8 in coöperative relation with the respective cam roller 9, and rotation of the latter serves to elevate the cam yoke and thereby operate the respective escapement 40 to deliver a matrix from the corresponding channel of the magazine. In the present embodiment of the invention, means is interposed between the keyboard mechanism and the escapements to take up or compensate 45 for overthrow or excess motion of the cam yoke, such excess motion being preferably provided in order to allow for wear of the cam roller and the associated parts. In the present instance, the escapements are 50 actuated by a set of vertically movable reeds 12 which are guided by the bars 13, each reed resting on and coöperating with an actuator which is operated by a corresponding cam yoke. In the preferred form, each 55 actuator embodies a plunger 14 which is fitted to operate vertically in the cam frame 5 and the upper end of this plunger forms a head which coöperates with the bottom of its respective reed. The plunger is 60 formed with a chamber 15 and an auxiliary plunger 16 is provided which is capable of moving axially in the chamber of the plunger 14 and is permitted a limited movement with respect to the plunger 14 by the 65 transverse pin 17 which operates within

the limits of the slots 18 formed in the walls of the plunger 14. A spring 19 is contained in the chamber 15 of the plunger 14 and bears at its ends against the plungers 14 and 16 respectively. The lower end of each 70 auxiliary plunger 16 is adapted to be engaged by the respective cam yoke when the same rises and the spring 19 then serves to transmit the movement of the auxiliary plunger 16 to the plunger 14 and the latter 75 will actuate its respective reed and the reed in turn will operate its respective escapement to release and cause delivery of a matrix from the corresponding channel of the magazine. When, however, the cam yoke 80 has an excess motion, the plungers 14 and 16 will move in unison until the escapement has reached the limit of its movement, and further movement imparted to the plunger 16 by the cam yoke causes compression of 85 the spring while the plunger 14 remains at rest, the spring constituting a yielding or compensating connection between the cam yoke and the reed.

The magazine 20 is shown in the present 90 instance as provided with the usual channels 21 to contain the matrices, the matrices being fed to the escapements and to the mouth of the magazine by gravity. The improved escapement mechanism provided by the 95 present invention embodies a set of escapements corresponding in number and position to the magazine channels, each escapement in the preferred form of the invention embodying a member 22 which is of segmental form and made in one piece. Each escapement member in the present instance is substantially semi-circular in form and it has a concentric inner bearing edge 23, the ends of the member forming pallets or stops 100 24 and 25 to coöperate with the ears on the matrices and thereby control the movements thereof toward the mouth of the magazine. Each escapement member is also provided 105 with a lug or projection 26 to coöperate 110 with a restoring spring, and an actuating projection 27 to coöperate with the corresponding reed, the under side of the magazine being preferably formed with a shoulder 28 which serves as a limiting 115 stop to arrest further movement of the escapement when the latter has been actuated by the reed to release a matrix. The present invention avoids the use of a pivot pin for each escapement member, a mounting being 120 provided for the escapements which consists preferably of a bar 29 which may be secured by screws 30 to the under side of the magazine, and this bar is formed with a number of concentric segmental grooves 31 125 which correspond in number and arrangement to the escapement members, these segmental grooves in the bar receiving the different escapement members and causing the same to oscillate about a given axis and pre- 130

venting lateral displacement thereof. According to the present invention, the axis of oscillation of the escapement members is located preferably on a line between the pallets or matrix-engaging ends thereof and is within the channel portion of the magazine and the arc of each escapement member, and its respective groove 31 in the bar 29 is concentric with a circle the diameter of which is equal to the distance between the projections or ends 24 and 25 of the escapement member. Also, each groove 31 in the bar 29 is so formed that it provides a cylindrical bearing for the respective escapement, the axis of which bearing is at a right angle to the plane of the respective escapement and the corresponding matrix channel of the magazine, this right angular relation between the escapements and the axes of their bearings being maintained across the width of the magazine, notwithstanding the fact that the matrix channels in the magazine are convergent, as shown in Fig. 5, and the escapements bear a corresponding convergent relation. The upper side of the bar 29 which in the present instance forms a portion of the bottom of the magazine is formed with grooves or channels 32 which constitute continuations of the channels or grooves 21 in the bottom of the magazine. Each escapement is provided with a spring 33 which is supported by a block 34 and acts on the lug or projection 26 of the escapement to counteract the respective reed and to restore the escapement to normal position after each actuation thereof. A guard or cover plate 35 is also provided which is secured to the under side of the magazine, it forming a housing for the springs 33 to protect the same and it has a lip or extension 36 which bears on the under sides of the escapement members to retain them in their respective bearings provided by the bar 29.

The operation of the mechanism shown may be briefly described as follows:—When the key bar 2 is elevated by manipulation of its respective key lever 1, the cam yoke 6 will be lowered, permitting the corresponding cam 8 to be rotated by reason of its engagement with the continuously revolving cam roller 9, the cam yoke being thereby elevated and the upward movement of the cam yoke will carry it into engagement with the auxiliary plunger 16 and continued rising movement of the cam yoke will cause the plunger 14 and its corresponding reed to be elevated through the medium of the spring 19 which is operated by the plunger 16. The reed will act on the actuating projection 27 of its corresponding escapement, causing the same to move from the position shown in Fig. 2 into the position shown in Fig. 3, the projection 25 on the escapement thereby releasing the lowermost matrix in the respective magazine channel and the projec-

tion 24 on the escapement engaging and arresting the following matrix in said channel. While the escapement is being moved into the position shown in Fig. 3, the plungers 14 and 16 will move in unison, but when the escapement has reached the limit of its movement, any further movement imparted to the plunger 16 by the cam yoke will cause compression of the spring 19 owing to the arresting of the movement of the plunger 14 and its respective reed. When the keyboard mechanism has returned to normal position, the reed and its corresponding plunger 14 will descend and the escapement will be restored to its normal or initial position by its respective spring.

I claim as my invention:—

1. In a linotype machine, a magazine having converging channels for the matrices, and a matrix-controlling escapement having an axis of motion located within said channel and at a right angle to the plane thereof. 85
2. In a linotype machine, the combination of a matrix-containing magazine having converging channels, and matrix-controlling escapements, each having an axis of motion located in a line between the matrix-engaging portions of the escapement and at a right angle to the plane of its respective channel. 90
3. In a linotype machine, an escapement having a bearing of arc form with matrix-controlling pawls at the ends of the arc, and a mounting to coöperate with said bearing. 95
4. An escapement embodying an arc-shaped member having matrix-engaging portions toward the ends thereof, and a mounting having an arc-shaped bearing coöperative with said member, the diameter of said bearing being located between said matrix-engaging portions. 100
5. The combination of a matrix-containing magazine having converging matrix-guiding channels, a set of escapements for controlling the delivery of matrices therefrom, each escapement being arc-shaped, and a bar extending transversely of the magazine and grooved to form lateral guides and cylindrical bearings for the escapements, the axis of each cylindrical bearing being at a right angle to the plane of its respective matrix channel. 110
6. The combination of a magazine having converging matrix channels in the bottom thereof, a set of escapements for controlling the delivery of matrices therefrom, and a bar extending transversely across the bottom of the magazine and having grooves in its upper surface constituting continuations of said matrix channels, the under side of the bar having a set of arc-shaped grooves to form lateral guides and cylindrical bearings for the escapements, the axis of each cylindrical bearing being at a right angle to the respective matrix channel. 115
7. The combination of a magazine having converging matrix channels in the bottom thereof, a set of escapements for controlling the delivery of matrices therefrom, and a bar extending transversely across the bottom of the magazine and having grooves in its upper surface constituting continuations of said matrix channels, the under side of the bar having a set of arc-shaped grooves to form lateral guides and cylindrical bearings for the escapements, the axis of each cylindrical bearing being at a right angle to the respective matrix channel. 120
8. The combination of a magazine having converging matrix channels in the bottom thereof, a set of escapements for controlling the delivery of matrices therefrom, and a bar extending transversely across the bottom of the magazine and having grooves in its upper surface constituting continuations of said matrix channels, the under side of the bar having a set of arc-shaped grooves to form lateral guides and cylindrical bearings for the escapements, the axis of each cylindrical bearing being at a right angle to the respective matrix channel. 125
9. The combination of a magazine having converging matrix channels in the bottom thereof, a set of escapements for controlling the delivery of matrices therefrom, and a bar extending transversely across the bottom of the magazine and having grooves in its upper surface constituting continuations of said matrix channels, the under side of the bar having a set of arc-shaped grooves to form lateral guides and cylindrical bearings for the escapements, the axis of each cylindrical bearing being at a right angle to the respective matrix channel. 130

7. The combination of a matrix-containing magazine having converging matrix channels, a set of escapements for controlling the delivery of matrices therefrom, each escapement being arc-shaped, and a bar extending transversely beneath the magazine and grooved to form guides and cylindrical bearings for the escapements, the axis of each cylindrical bearing being at a right angle to its respective matrix channel.
8. The combination of a matrix-containing magazine having converging matrix channels, a set of escapements set into the bottom of the magazine for controlling the delivery of matrices therefrom, each escapement being arc-shaped, a bar extending transversely beneath the magazine and grooved to form lateral guides and cylindrical bearings for the escapements, the axis of each cylindrical bearing being at a right angle to its respective matrix channel, and a guard having a portion below said bar and escapements to retain the latter in the grooves of the bar.

9. In a machine of the linotype class, the combination of a matrix-containing magazine having converging matrix-guiding channels, and a set of matrix-controlling escapements, each escapement being in one piece and mounted to rock on an axis which is at a right angle to the plane of its respective channel and the center of which is substantially in the path of the matrices.

10. In a linotype machine, the combination with a magazine having matrix channels converging toward the delivery end, of a series of escapements mounted to rock about cylindrical bearings, the axis of each bearing being perpendicular to the length of its respective channel.

In testimony whereof I have hereunto set my hand in presence of two subscribing witnesses.

THOMAS S. HOMANS.
